MEANS FOR PREVENTING STRINGS FROM SLIPPING OFF PULLEYS IN TOYS AND THE
LIKE

Application filed May 10, 1928, Serial No. 276,774, and in Germany October 20, 1927.

The present invention relates to protective means for preventing strings, cords and the like from slipping off grooved pulleys or rollers in toys and similar articles. In toys, particularly those which are made of sheet material and in which the movement of the working parts is brought about by means of a comparatively loose string, cord, chain or the like running over a pulley or roller, the said string or the like has hitherto been very liable to escape from the groove in the pulley or roller during transport of the toy or when for any other reason the toy has been turned upside down. A replacing of the tensile member in question can only be accomplished with difficulty, particularly when the toy is a closed article, especially as such toys are usually operated not by mechanics but by children or other persons who are not capable of carrying out very easily the requisite manipulations.

In order to obviate this difficulty I have provided a protective plate, which is fitted close over the string to be protected, at the point where it runs in the groove on the pulley. For this purpose, at the upper part of the pulley, at the level of the bed of the groove in the pulley in which the string rests, is fitted a plate or the like surrounding the pulley and the string, and comprising an aperture which is accurately dimensioned so as just to leave the pulley free in the centre thereof, while preventing the string from slipping down over the edge of the pulley. Owing to this narrowness of the space between the pulley and the edge of the aperture in the plate, if the string becomes loose or rises above the pulley in a curved form owing to the toy being turned upside down, it must always slip back again into the groove when the toy is turned over again and the string pulled tight by a weight or the like, whereas without this limitation as to the size of the aperture, the string would slip down beside the pulley and drop directly on to the shaft of the pulley, thereby preventing the toy from working. The plate may be of any convenient shape and may be secured to the casing in any manner that appears desirable, as for example with lugs or the like.

The invention is diagrammatically illustrated by way of example in various constructional forms in Figures 1 to 4 of the accompanying drawings:—

The figures show one constructional form of the invention, with two protective plates of the kind already mentioned, and a third protective plate of a different kind, Figs. 1 and 2 being sectional elevations, Fig. 3 a plan, and Fig. 4 a sectional plan of the third protective plate alone on the line 4—4 in Fig. 1.

In all the figures all the parts that are not essential are as far as possible omitted.

In the device shown in the drawings 3 is a shaft (here shown quite short) carrying a pulley 6, over which passes a string 7. 18 is a plate extending transversely across the toy at the level of the bed of the groove at the top of the pulley. 19 is the aperture in the plate 18. The plate 18 is secured at 20 to the casing 4.

24 is a substantially U-shaped plate secured at 25 beneath the plate 18 and provided with an aperture 26 on a level with the bed of the groove on the under side of the pulley, this aperture 26 being of such dimensions that it just allows the string 7 to pass through.

It is advantageous to provide at a suitable position, for instance in a plate 27 carrying the part 4 of the casing, as shown in Figures 1 to 4, separate holes 28 through which the string 7 can pass, for the purpose of preventing the parallel parts of the string from becoming twisted or entangled in the event for example of the toy being turned upside down.

The material of the toy is preferably of sheet iron or other sheet material, but celluloid, wood, or any other suitable material may be employed.

What I claim is:—

1. Protective means for preventing strings, cords and the like from slipping off grooved pulleys and rollers in toys and similar articles, comprising plates located at the same distance from the axis of the pulley as the bed of the groove against which the string bears, and at the parts of the pulley at which protection is required, each of said plates being formed with an aperture which fits round the pulley as closely as is possible without touching the pulley as it revolves and

without touching the string when said string is bearing against the bed of the groove.

2. Protective means for preventing strings, cords and the like from slipping off grooved pulleys and rollers in toys and similar articles, comprising a plate at the level of the bed of the groove on which the string rests at the top of the pulley, said plate being formed with an aperture which fits round the pulley as closely as is possible without touching the pulley as it revolves and without touching the string when said string is bearing against the bed of the groove, and an additional plate, located at a greater distance from the axis of the pulley, said additional plate being formed with two holes through which the string can pass, to prevent said string from becoming tangled when slack.

3. Protective means for preventing strings, cords and the like from slipping off grooved pulleys and rollers in toys and similar articles, comprising a plate located at the same distance from the axis of the pulley as the bed of the groove against which the string bears, at the part of the pulley at which protection is required, said plate being formed with an aperture which fits round the pulley as closely as is possible without touching the pulley as it revolves and without touching the string when said string is bearing against the bed of the groove, and an additional plate, located at a greater distance from the axis of the pulley, said additional plate being formed with two holes through which the string can pass, to prevent said string from becoming tangled when slack.

4. Protective means for preventing strings, cords and the like from slipping off grooved pulleys and rollers in toys and similar articles, comprising plates located at the same distance from the axis of the pulley as the bed of the groove against which the string bears, at the parts of the pulley at which protection is required, each of said plates being formed with an aperture which fits round the pulley as closely as is possible without touching the pulley as it revolves and without touching the string when said string is bearing against the bed of the groove, and an additional plate, located at a greater distance from the axis of the pulley, said additional plate being formed with two holes through which the string can pass, to prevent said string from becoming tangled when slack.

5. In testimony whereof I have signed my name to this specification.

ERNST PAUL LEHMANN.
